UNITED STATES PATENT OFFICE.

WILLIAM HAAS AND CHARLES W. RINGELSPAUGH, OF DAYTON, OHIO, ASSIGNORS TO THE WILLIAM HAAS COMPANY, OF DAYTON, OHIO, A CORPORATION OF OHIO.

VALVE.

1,322,012.

Specification of Letters Patent.

Patented Nov. 18, 1919.

Application filed January 2, 1919. Serial No. 269,336.

To all whom it may concern:

Be it known that we, WILLIAM HAAS and CHARLES W. RINGELSPAUGH, citizens of the United States, residing at Dayton, in the county of Montgomery and State of Ohio, have invented certain new and useful Improvements in Valves, of which the following is a specification, reference being had therein to the accompanying drawing.

10 This invention relates to improved valves and has for its particular object to provide an improved regulating valve for steam radiators.

15 An object of the invention is to provide a valve adapted for right or left hand, vertical or horizontal connections, being in effect interchangeable or universal in character and therefore adaptable to any standard form of radiator connections.

20 Our improved valve is also adaptable to the two general types of steam radiators, viz., single pipe system and double pipe system. As applied to the double type system the inlet port of the valve may be regulated 25 by means of a handle having a pointer co-operating with a graduated scale. Thus the volume of steam passing to the radiator may be controlled, increased or diminished as may be desired. As used with a single 30 pipe system the valve may be opened to full capacity and closed instantly merely by moving the valve controlling handle to the limits of its movement, respectively, which as here shown is substantially 120 degrees.

35 Various incidental improvements have been carefully worked out in the development of our invention which in their collective effect tend to make the valve distinctly meritorious, especially as applied to radiators of the single pipe type. These features consist generally of ground-in joint construction which acts to prevent the escape of steam around the valve stem either as the valve is closed or open; the stuffing box is so 40 designed that it may be packed under pressure; the valve seat is disposed in a vertical plane and otherwise shaped to prevent the accumulation of foreign matter thereon and thereby preventing the proper functioning 45 of the valve; the operable parts are essentially of simple, durable construction and of a character which will not be affected by the corrosion of the parts or the action of the heat thereon, thus insuring the normal operation of the valve under all conditions.

The valve is in the important particulars stated, an improvement of the type of steam radiator valve which provides for the introduction of steam and the simultaneous return of the condensation through the same 60 port, the steam entering the valve through the upper portions of the port, and the condensed moisture being heavier than the steam, passing from the valve through the lower portion of the port.

65 In the accompanying drawings,

Figure 1 is a side elevation of the valve with the operating parts horizontally disposed and showing in dotted lines portions of the interior arrangement of the mechanism;

Fig. 2 is a longitudinal cross sectional view of the valve with the operable parts vertically disposed;

Fig. 3 is a cross sectional view of the valve 75 casing taken on the line 3—3 of Fig. 1;

Figs. 4, 5 and 6 are detail views, respectively, of the valve head or piston, the stem for controlling the same and the conical valve projection.

80 Fig. 7 is a detailed view of a valve indicator for determining the relative positions of the valve.

The valve casing consists of an integral housing 1, best shown in section in Fig. 3, 85 provided with an extension 2 and intake aperture 3, threaded internally in the usual manner to be connected to the steam supply pipe; the valve casing being connected to the radiator by means of an externally 90 threaded extension 4 and an aperture 5, the connection being made in any suitable manner as by a union consisting of a short section of pipe 6 and the adjustable nut 7. The valve casing is further provided with an 95 extension 8 threaded internally and having an aperture 9 normally closed by a plug 10. Oppositely disposed projections 11 and 12 provided, respectively, with threaded apertures 13 and 14 are also provided in the 100 valve casing, either one of the apertures being normally closed by a plug 15 and the other provided with adjustable nuts 16—17 which are provided with apertures constituting a bearing for one end of the stem 105 for regulating the valve piston. The nut 17 is threaded at one end to receive the nut 16, and at the opposite end to be secured to the casing 1, the central portion of the nut being hollow, as at 18, to provide a suitable 110

stuffing box for the valve actuating stem. A cap 19 is provided to add finish to the connection formed between the nuts 16 and 17.

The valve casing is provided with an internal chamber 20 merging at one end thereof adjacent the outlet aperture 5 into a chamber 21. At the juncture of the outlet 5 with the chamber 21 and integral with the casing 1 an annular wall 22 is transversely disposed between the walls of the casing and is provided on the inner side thereof with a valve seat 23. Also extending inwardly from the casing 1 and integral therewith are ribbed portions 24, the inner edges of which act as guides for the valve piston to retain the same in proper relation to the valve seat 23.

The valve piston consists of a main body portion 25 terminating at one end thereof in a piston head 26 which fits snugly between the guiding surfaces of the ribbed portions 24, the flat face thereof being adapted to be seated upon the surface 23 of the annular ring portion 22, the seat portion of the piston consisting preferably of a composition disk 26^a which acts to more effectually close the valve to prevent leakage thereof. At its opposite end the valve piston is provided with a shoulder 27 and a stem 28, the latter being adapted to enter and coöperate with an aperture 10^a provided in the plug nut 10 which acts to guide one end of the valve piston. The valve piston is further provided through the body portion thereof with an oblong aperture 29 whereby the piston may be raised and lowered relative to the valve seat.

When the valve is used in connection with a two pipe radiator system the piston head 26 may be provided on the flat face thereof with a conical projection 26^b detachably secured to the piston, as here shown, or made integral therewith; the tapered end thus formed acting through the operation of the valve controller handle to gradually increase or decrease the capacity of the port opening leading to the radiator. In single pipe radiator systems the valve piston head is preferably made flat to provide for quick opening and closing of the valve.

The valve piston is regulated by means of the actuating stem or shaft 30 which is provided with the crank or eccentric portion 31 adapted to coöperate with the aperture 29 of the valve piston to regulate the same relative to the valve seat. One end 32 of the valve actuating stem is adapted to be supported in a bearing 15^a provided in the plug 15. The end 30 of the valve stem projects through nuts 16 and 17 and has secured to its outer end in any suitable manner a controller handle 33 by means of which the valve may be regulated. At its central portion, adjacent one end of the crank portion 31, the valve actuating stem is provided

with a tapered or cone-shaped portion 34, adapted to coöperate with a corresponding depression 35 formed in the inner end of the nut 17, thus constituting a conical bearing and acting to more effectually prevent escaping of steam about the valve stem 30.

From the foregoing description it will be clear that our improved valve is essentially a quick-acting valve, having a wide range of adaptability being practically universal with respect to standard radiator connections, either of single or double pipe radiator systems. The construction of the valve is such that corrosion of the parts will not affect the free and easy operation thereof under all conditions, either under pressure or open. Opening and closing of the valve to full extent being accomplished by a slight movement of the controller handle, it is obvious that an important advantage is realized over types of valves requiring a number of turns of the valve stem to adjust the valve to full open and closed positions. In general construction our valve has been provided with improvements and refinements which together with the marked features of novelty result in a valve of superior merit, of simple, durable construction, of universal character with respect to its interchangeability and adaptability to various types of radiator construction.

In addition to its other important advantages, the improved valve is further especially adaptable to radiators inclosed by a grille or otherwise incased in such a manner that an ordinary valve would not be readily accessible and therefore could not be conveniently regulated. With the present valve this difficulty is readily met by merely lengthening the valve actuating stem to project through the casing of the inclosure, this being made possible by the universal feature of the valve which makes it adaptable under a wide range of variable conditions.

Having thus fully described our invention, what we claim as new and desire to secure by Letters Patent, is:—

1. In a radiator valve, a casing comprising an inlet port and oppositely disposed bearings arranged substantially at right angles to said port and a bearing arranged intermediate said bearings substantially at right angles thereto, a valve piston supported in the last named bearing and operable relative to said port, a valve stem supported in said opposite bearings and adapted to operate said piston, whereby the valve stem may be interchangeably connected to said piston.

2. In a radiator valve, a casing comprising an inlet port and oppositely disposed bearings arranged substantially at right angles to said port and a bearing arranged intermediate said bearings substantially at right angles thereto, a valve piston sup-

ported in the last named bearing and operable relative to said port, a valve stem supported in said opposite bearings and adapted to operate said piston, whereby the valve 5 stem may be interchangeably connected to said piston and an outlet port coöperating with the inlet port.

3. In a radiator valve, a casing comprising an inlet port, and oppositely disposed 10 bearings arranged substantially at right angles to said port and a bearing arranged intermediate said bearings substantially at right angles thereto, a valve piston supported in the last named bearing and operable 15 relative to said port, a valve stem rotatably supported in said opposite bearings to operate said piston, whereby the valve stem may be rotatably and interchangeably connected to the valve piston.

20 4. In a radiator valve, a casing comprising an inlet port and oppositely disposed bearing arranged substantially at right angles to said port and a bearing arranged intermediate said bearings substantially at 25 right angles thereto, a piston supported in the last named bearing and having a cam slot and operable to open and close said port, a valve stem supported in said opposite bearings and having an eccentric portion 30 adapted to engage the cam slot of the piston, whereby the valve stem may be interchangeably connected to the valve piston.

5. In a radiator valve, a casing comprising an inlet port and oppositely disposed 35 bearings arranged substantially at right angles to said port and a bearing arranged intermediate said bearings substantially at right angles thereto, a piston supported in the last named bearing and having a cam 40 slot and operable to open and close said port, a valve stem rotatably supported in said opposite bearings having an eccentric portion adapted to engage the cam slot of the piston, whereby the eccentric portion of the valve 45 stem will engage the cam slot of the valve piston, and full opening and closing movements, respectively, may be imparted to the valve piston by partial rotation of the valve stem.

50 6. In a radiator valve, a casing comprising an inlet port and oppositely disposed bearings arranged substantially at right angles to said port and a bearing arranged intermediate said bearings substantially at 55 right angles thereto, a piston supported in the last named bearing and operable to open and close said port, and a valve stem rotatably supported in said opposite bearings, eccentrically connected with said piston and 60 adapted to actuate the valve piston to full open or closed position by partial rotation of said stem.

7. In a radiator valve, a casing comprising inlet and outlet ports, regulating mech-

anism supported in said casing in operable 65 relation to said ports, an actuator eccentrically connected to said regulating mechanism, and means whereby the actuator may be interchangeably connected to the regulating mechanism, whereby said valve is adapted 70 for right or left hand connections to the radiator.

8. In a radiator valve, a casing comprising inlet and outlet ports, regulating mechanism supported in said casing and operable 75 relative to said ports, an actuator eccentrically connected to said regulating mechanism and interchangeable parts detachably secured in said casing whereby the valve may be rendered universally adaptable to 80 variable radiator connections of standard construction.

9. In a radiator valve, a casing comprising a port, a valve piston adapted to open and close said port, interchangeable parts 85 detachably secured in said casing whereby the valve may be rendered universally adaptable to variable radiator connections of standard construction, a valve stem eccentrically connected to the piston and extending substantially at right angles thereto, means to limit the movements of the piston, whereby said port may be opened and closed to full capacity, respectively, by a partial rotation of the valve stem and means to indicate the open and closed positions of the 90 valve.

10. In a radiator valve, a casing, an annular wall extending inwardly from said casing and having a port therein, a piston 100 coöperating with said port and adapted to be seated on said annular wall and having a tapered end projecting into the port opening, guides extending inwardly from said casing and acting to retain the piston in axial alignment with said port, and actuating means and an indicator whereby said piston may be controlled to regulate said port.

11. In a radiator valve, a casing an annular wall extending inwardly from said casing and having a port therein, a piston co-operating with said port and adapted to be seated on said annular wall, said piston having a stem projecting from one end thereof and coöperating with an aperture in said 115 casing and comprising a cylindrical portion at the other end thereof coöperating with guides extending inwardly from said casing whereby the piston is retained in axial alignment with the port, and means for adjusting the piston in predetermined positions relative to said port and graduated 120 means for indicating the adjusted positions.

In testimony whereof, we affix or signatures.

WILLIAM HAAS.

CHARLES W. RINGELSPAUGH.
